W. G. TURNER,
MEANS AND METHOD OF COUPLING COTTON TIES,
APPLICATION FILED MAY 25, 1918.

Patented Mar. 2, 1920.

William G. Turner,
Inventor
By *Burdorf & Roselittle*,
Attorneys

UNITED STATES PATENT OFFICE.

WILLIAM GRUBB TURNER, OF MEMPHIS, TENNESSEE.

MEANS AND METHOD OF COUPLING COTTON-TIES.

1,332,645.

Specification of Letters Patent.

Patented Mar. 2, 1920.

Application filed May 25, 1918. Serial No. 236,593.

To all whom it may concern:

Be it known that I, WILLIAM GRUBB TURNER, a citizen of the United States, residing at Memphis, Shelby county, and 5 State of Tennessee, have invented and discovered certain new and useful Improvements in Means and Methods of Coupling Cotton-Ties, of which the following is a specification.

10 My said invention consists in certain improvements in the method and means employed in coupling the free ends of metal bands such as are commonly used as ties in baling cotton, all of which will be herein- 15 after more fully described and claimed.

Referring to the accompanying drawings which are made a part hereof, and on which similar reference characters indicate similar parts,

20 Figure 1 is a perspective view in which is illustrated the lapped ends of a tie for a cotton bale as they appear just previous to the operation of forming the fold or twist preparatory to securing them together.

25 Fig. 2, a similar view showing the parts as they appear after being folded or twisted, and

Fig. 3, a similar view showing the folded or twisted portion as finally secured to- 30 gether by the clamping member.

In the operation of baling cotton, the ends of the tie are threaded through trans- 35 verse channels in the upper and lower plat- ens of the compress, as is well understood.

35 The tie is drawn as taut about the bale as possible and the free ends buckled together by manual labor. In the practice of my present invention said ends 10 and 11 are lapped one over the other as shown in Fig.

40 1, the clamping member 12 being first placed upon the end 10 above the point where the lap is to be made. A tool 15 such as is illustrated in Fig. 1, having a bifur- 45 cated end, is then placed over the lap with

its upper edge near the end of the outside member 11. A handle is applied to the squared shank 26 of said tool and the same is turned to double the ends over upon each other and form a fold or twist in said

50 lapped ends and the operation at the same time serves to draw the bale tie taut around the bale.

The member 12 is of the form clearly 55 illustrated in the several figures of the drawing. It is provided with a notch 16 in its opposite sides which enables it to pass down over the fold and embrace the end of

the twisting tool before the twisting tool is removed, as indicated in Fig. 2, and thus start the clamping member over the fold be- 60 fore said fold is enlarged or opened under the strain or spring expansion of the metal itself. The tool being removed the clamp- 65 ing member is slid down to the position shown in Fig. 3, the lip 17 being bent in by a blow with a hammer or other appropriate 70 tool to engage the top of the fold and prevent the clamping member from passing over said fold and also to retain it in its proper position around the fold and thus prevent any undoing thereof.

By this means the bale tie may be quickly secured and at the same time drawn taut so as to prevent any undue expansion of the bale after the tie is applied.

Having thus fully described my said in- 75vention what I claim as new and desire to secure by Letters Patent, is:

1. A securing device for bale ties comprising a clamping member adapted to slide over a fold formed in the overlapped ends of the tie and having a notch in one side adapted to embrace a twisting or folding tool and a lip to retain the member in place, substantially as set forth.

2. The method of coupling the ends of a bale tie together which consists in applying a twisting tool over the lapped ends of said tie, turning said tool to double said ends upon each other, sliding a clamping mem- 90 ber forward to embrace said doubled over portion and the edge of the tool into position to hold said doubled portion from ex- pansion, removing the tool, and then fixing said clamping member in position, substan- 95 tially as set forth.

3. A bale tie joint formed by doubling over the lapped ends of the bale tie, said doubled portion being surrounded and held together by a clamping member formed 100 with a tongue or lip adapted to retain said clamping member in position and with notches in its sides adapted to permit said clamping member to pass partly to position before the twisting tool is removed, sub- 105 stantially as set forth.

In witness whereof, I have hereunto set my hand and seal at Washington, District of Columbia, this twenty-third day of May, A. D. nineteen hundred and eighteen.

WILLIAM GRUBB TURNER. [L. s.]
